INDUCTION TRAIN CONTROL SYSTEM

Filed May 4, 1923

UNITED STATES PATENT OFFICE

FRED M. ROSENZWEIG, OF NIAGARA FALLS, NEW YORK, ASSIGNOR TO THE REGAN SAFETY DEVICES COMPANY, INC., OF NEW YORK, N. Y., A CORPORATION OF NEW YORK

INDUCTION TRAIN-CONTROL SYSTEM

Application filed May 4, 1923. Serial No. 636,553.

This invention relates to automatic train control systems, and has special reference to the provision of an improved automatic train control system of the induction type.

A principal object of the present invention comprehends the provision of an induction train control system in which train carried mechanism is operated to produce a plurality of different effects responsive to the cooperation between vehicle carried and roadside inductor means, the construction and the cooperation being such that the vehicle carried inductor means is influenced by the roadside inductor means to produce a controlling, such as a tripping action of the vehicle carried mechanism under one roadside condition, and is influenced by the roadside inductor means under one or more different roadside conditions to produce a resetting action of the vehicle carried mechanism.

A further principal object of the present invention relates to the provision of an inductive system of the type referred to in which the vehicle carried and roadside inductor means are operated by means of a vehicle carried source of energy.

A still further principal object of the invention includes the provision of a system of the nature referred to in which the vehicle carried and roadside inductor means are constructed so as to cooperate for producing a controlling or tripping operation of the train carried mechanism under a "danger" roadside condition, and for producing a resetting action of the vehicle carried mechanism under a "safe" or "clear" roadside condition when the same has been tripped, the roadside inductor means being however inoperative to produce any change in the vehicle carried mechanism under a "safe" or "clear" roadside condition when the said vehicle carried mechanism has not been tripped.

Further objects of the invention include the provision of a simplified induction system in which a vehicle carried inductor is employed for energizing the vehicle carried mechanism, the said inductor being influenced by the roadside inductor means under one roadside condition for producing the controlling action of the vehicle carried mecha-

nism, the said energizing inductor being operative for energizing the roadside inductor means under another roadside condition to produce a modification of the controlling operation; the still further provision of a system of this nature in which the inductive means for producing a tripping action of the train carried mechanism is combined in a unit circuit with the inductive means for producing a resetting operation of the vehicle carried mechanism; the still further provision of a system of this nature in which the parts of the system are coordinated to produce "proceed", "proceed at caution" and "stop" effects on the vehicle in response to "clear", "caution" and "danger" conditions on the roadside; and the provision of improved means for amplifying the energy inductively received for producing the resetting operation of the vehicle carried mechanism.

To the accomplishment of the foregoing and such other objects as may hereinafter appear, my invention consists in the elements and their relation one to the other, as herein-after particularly described and sought to be defined in the claims, reference being had to the accompanying drawings which show a preferred embodiment of my invention and in which:

Fig. 1 is a diagrammatic view showing the vehicle carried mechanism and the roadside mechanism associated therewith,

Fig. 2 is a diagrammatic view showing one means for amplifying the energy inductively received by parts of the vehicle carried mechanism, and

Fig. 3 is a view of a modified form of energy amplifying means.

Before describing in detail the system of my invention, I will briefly premise that in my inductive train control system a train control mechanism, such as a valve V which may control the train line of an air brake system, is operated by means of train carried energy such as the alternating current generator G, and is controlled by the cooperation of a vehicle carried inductive means generally designated as A and a roadside inductor means generally designated as B, the

vehicle carried and roadside inductor means A—B cooperating to produce a controlling operation of the valve V under one or more roadside conditions such as a "danger" or "caution" condition, to modify the operation 5 of the valve V under other roadside conditions such as a "clear" or "caution" roadside condition and to prevent any controlling operation or modifying operation of the valve 10 V as when the train is running "clear" under "clear" roadside conditions, or when running at "caution" under "caution" roadside conditions.

The valve V may be any suitable valve for 15 controlling the flow of air in the train line of an air brake system, such valve being preferably of the type shown in the patent to A. G. Shaver No. 1,411,526 of April 4, 1922.

The valve V is controlled by means of an electromagnet 10 which is normally energized by 20 a vehicle carried circuit designated for convenience as *h* and comprising the generator G, conductors 11, 12 and 13, contact 14 which is normally closed by the energization of a 25 relay F, conductor 15, conductor 16, coil of electromagnet 10 and conductors 17, 18 and 19.

In the preferred embodiment of my invention the circuit *h* is controlled and operated to produce "proceed", "proceed at caution" 30 and "stop" effects in response to "clear", "caution", and "danger" roadside conditions. Under "clear" roadside conditions the circuit *h* is closed at the contact 14 due to the energization of the relay F, which relay is 35 deenergized under "danger" roadside conditions to effect the opening of the contact 14 and the opening and the deenergizing of the circuit *h* and electromagnet 10 respectively.

Under "caution" track conditions the circuit 40 *h* is controlled by a branch or partial circuit arranged in parallel with the contact 14, the said branch or partial circuit comprising the conductor 20, a speed circuit controller 21, the contacts of which are closed when the 45 vehicle is traveling at or below a predetermined speed and are opened when the vehicle exceeds such speed, conductor 22, contact 23 controlled by a relay H, and conductor 24.

Under "caution" track conditions the relay H 50 is energized to close the contact 23, placing the circuit *h* under the control of the speed circuit controller 21 so that when the speed of the vehicle under the "caution" track conditions is at or below the predetermined or 55 fixed speed, the electromagnet 10 is energized to permit the train to proceed under restriction; and when such speed of the vehicle is exceeded, the electromagnet 10 is deenergized to operate the train venting valve 60 V to bring the train to a stop.

The relays F and H are operated by means of the vehicle carried source of energy G and are controlled by the cooperation of the vehicle carried and roadside inductor means 65 A—B. The relay F comprises a two-element

relay having the field *f* and the armature *f'* arranged in series in a stick circuit which may be designated for convenience as *i* comprising the contact 25 controlled by the relay F, the conductor 26, conductor 27, the coil of an inductor element *b*, conductor 28, condenser 29, conductor 30, relay element *f*, conductor 31, relay element *f'*, conductor 32, and conductor 33. This circuit *i* is normally energized by a circuit, which for convenience 70 may be designated as *k*, comprising the generator G, conductor 11, conductor 34, the coil of an inductor element *a*, conductor 35 and conductors 18 and 19. The elements *a* and *b* are inductively related so that under normal conditions with the circuit *i* closed, the relay F is energized to maintain its contacts 75 14 and 25 closed.

The relay H also comprises a two-element relay having the field *h'* and the armature *h''* arranged in series in a circuit which may be designated as *l* comprising a contact 36 which is open under normal conditions and which is closed when the relay H is energized in response to "caution" conditions, a conductor 37, a conductor 38, a condenser 39, a conductor 40, the coil of the third inductor element *c*, the conductor 41, relay element *h''*, conductor 42, relay element *h'*, and conductor 43. The inductor *c* is also inductively 90 related to the energizing inductor *a*, so that when the circuit *l* is closed, the relay H will be energized from the energizing circuit *h* and the generator G. Condensers 29 and 39 are provided in the circuits *i* and *l* respectively, for the purpose of making these circuits normally substantially resonant. 100

Cooperating with the inductor elements *a*, *b* and *c* of the vehicle carried inductor means A, there are provided corresponding inductor elements *a'*, *b'* and *c'* forming part of the roadside inductor means B, the inductor elements *a'*, *b'* and *c'* being arranged in spaced relation between the rails of the track corresponding to the spacing of the vehicle carried inductor elements *a*, *b* and *c*, so that in the movement of the vehicle and the vehicle carried mechanism in the direction as indicated by the arrow in Fig. 1, the vehicle inductor elements will move over so as to be influenced by and to influence the corresponding roadside inductor elements. More specifically, the roadside inductor elements *a'*, *b'* are arranged to cooperate with the vehicle carried inductor elements *a* and *b* to produce a controlling operation of the vehicle carried relay F, and to this end the inductor elements *a'*, *b'* are arranged in series in a circuit which may be designated as *n* including the coil of the inductor element *a'*, the conductor 44, the coil of the inductor element *b'*, conductor 45, the coil of another roadside inductor *d'* the function of which 110 will be made clear hereinafter, conductor 46, a contact 47 closed under "clear" track con- 115

120

125

130

ditions and controlled by a distant roadside relay D, conductor 48, contact 49 closed under "clear" track conditions and controlled by a home or track relay T, conductor 50, condenser 51, and conductor 52, the condenser being provided in this circuit to correct the impedance factor thereof. Also the roadside inductor elements a' and c' are arranged for cooperation with the vehicle carried inductor elements a and c respectively to produce a controlling operation of the vehicle carried relay H, and to this end these roadside inductor elements are arranged in a circuit generally designated as n comprising the coil of the element a' , the conductor 53, the coil of the inductor element c' , conductor 54, the coil of another roadside element e' the function of which will be made clear hereinafter, conductor 55, a back contact 56 normally open and closed when the relay D is deenergized, conductor 48, contact 49, conductor 50, condenser 51, and conductor 52. With this described construction it will be clear that when the home and distant relays T and D are both energized, as under "clear" track conditions, the inductor circuit m will be closed; that when the distant relay D is deenergized, as under "caution" track conditions, the inductor circuit m will be opened and the inductor circuit n closed; and that when the home relay T is deenergized, this being in response to "danger" track conditions, the opening of the contact 49 will open both of the inductor circuits m and n .

35 The operation of the system thus far described is as follows: When the train is running without restriction between control stations, the energizing inductor a functions in the nature of the primary of a transformer, the secondary of which is the inductor b which is energized for operating the relay F to maintain the train control circuit h normally closed. When the train reaches a control station the vehicle carried inductor elements a and b move over the roadside inductor elements a' , b' , and when the conditions ahead are "clear", the vehicle inductors a , b are uninfluenced due to the fact that the roadside inductor circuit m is closed, the vehicle inductor elements being influenced, however, to produce a controlling condition in the relay F when the inductor circuit m is opened due either to "caution" or "danger" roadside conditions. With the circuit m open, the inductor elements a' and b' modify the reluctance of the magnetic circuits of the vehicle carried inductors a and b , the change in the reluctance of the magnetic circuit b having the effect of changing the impedance of the train carried circuit i , with the resulting effective deenergization of the control relay F. With the circuit m closed, however, in response to "clear" roadside conditions, the reluctance of the magnetic circuits is not substantially varied and the impedance of the circuit i is

70 maintained so that the relay F is uninfluenced. Thus under "danger" conditions the relay F is deenergized, opening the control circuit h at the contact 14 to bring the vehicle to a halt, and opening the stick circuit i to maintain the relay F deenergized after the train passes beyond the control station. Similarly when the train is running under "caution" conditions between control stations and the vehicle carried circuit l is closed for energizing the relay H as will appear further hereinafter, the vehicle carried inductor elements a and c function in the nature of a transformer, the element a acting as the primary or energizing inductor, and the element c as the secondary or receiving inductor for energizing the circuit l and maintaining the same energized. When a train running under "caution" conditions reaches a caution station, the circuit n is closed and the movement of the vehicle carried inductors a , c over the roadside inductors a' , c' produces no controlling effect on the circuit l . If, however, a train running under "caution" conditions reaches a "danger" control station, the vehicle inductor elements a and c are influenced by the inductor elements a' , c' in the open circuit n to change the impedance of the train carried circuit l for producing an effective deenergization of the relay H, the deenergization of this relay causing the opening of the control circuit h at the contact 23 to bring the vehicle to a halt and causing the opening of the stick circuit l which remains open after the train has moved beyond the control station.

80 It will thus be seen that with the provision of the system described, a train running under "clear" conditions will pass a "clear" station uninfluenced and a train running under "caution" conditions will pass a "caution" station uninfluenced, a controlling operation of the train being, however, obtained when a train running under "clear" conditions reaches a "caution" or "danger" station and when a train running under "caution" conditions reaches a "danger" station, the controlling effect consisting in a tripping of the train mechanism, this controlling effect persisting after the train has moved beyond the controlling point.

85 After a controlling or "tripping" operation of the train carried mechanism is produced, the said train mechanism is automatically reset under the proper roadside conditions. Thus after the relay F is deenergized the same may be automatically reset when the train reaches a control station indicating "clear" conditions ahead, and the relay H may be likewise reset when the train reaches a station indicating "caution" conditions ahead.

90 For resetting the relay F, I preferably provide a reset partial circuit including the conductor 57 and a contact 58 arranged in paral-

lel with the contact 25, the contact 58 being controlled by an indication receiver F' which may be of the two-element type having a field f² always energized from the vehicle 5 carried generator G and connected thereto by means of the conductors 59 and 60 connected to the lines 19 and 11 respectively, and an armature f³ included in a circuit which may be designated as o comprising the armature 10 f³, conductor 61, coil of a vehicle carried inductor d and conductor 62, the said inductor d being arranged to move over the roadside inductor element d' heretofore mentioned. For resetting the relay H, I preferably provide 15 a resetting partial circuit comprising a conductor 63, conductor 64, contact 65, conductor 66 and conductor 67, this partial circuit being arranged in parallel with the stick contact 36 of the relay H, the contact 65 being 20 controlled by an indication receiver H' which may also be of the two-element type having the field h² energized from the generator G and connected thereto by means of the conductors 68 and 69, and the armature h⁴ arranged in a circuit which may be 25 designated as p comprising the armature h⁴, conductor 70, coil of a vehicle carried inductor element e and conductor 71, the inductor element e being arranged to move over the 30 roadside inductor element e' heretofore mentioned.

The operation of the resetting means is substantially as follows: After the vehicle 35 carried relay F has been tripped in response to either "danger" or "caution" roadside conditions, the said relay F is reset when the vehicle passes a station indicating "clear" conditions ahead by the closing of the contact 58 which effects the closing of the vehicle 40 circuit i. Under such "clear" track conditions the roadside inductor circuit m is closed and when the vehicle inductor means moves over the roadside inductor means, the vehicle inductor a energizes the roadside inductor 45 a', inductor element a' acting now in the nature of an impulse receiving inductor, the impulse being transmitted to the roadside inductor element d' which in turn transmits the same to the vehicle receiving inductor d. 50 The impulse received by the vehicle receiving inductor d is sufficient to energize the relay element f³ for operating the relay F' to close the contact 58 of the reset circuit. It will be noted that the closing of the roadside inductor 55 circuit m obviates any change taking place in the resonant vehicle circuit i, so that the closing of the contact 58 of the reset partial circuit effects the energization of the relay F by the cooperation of inductor elements a, b for the closing of the contacts of this 60 relay. Although the cooperation of the reset inductors d and d' is but momentary, it will be noted that the energizing of the relay F closes the contact 25, thereby closing the 65 stick or holding circuit for the said relay F.

When a train reaches a station indicating "caution", the relay H is reset by the closing of the contact 65, the closing of this contact effecting the closing of the vehicle carried circuit l. Under such "caution" conditions the roadside inductor circuit n is closed as hereinbefore pointed out, and when the vehicle inductor elements move over the roadside inductor elements, the vehicle inductor element a energizes the roadside inductor element a', the latter acting in the nature of an impulse receiving inductor, the received impulse energizing the transmitting inductor e' for producing an impulse which in turn is transmitted to the vehicle receiving inductor e, the said transmitted impulse being sufficient for energizing the relay element h⁴ of the relay H', the energization of this relay effecting the closing of the reset circuit contact 65. It will again here be noted that due to the closing of the roadside inductor circuit n the resonance of the vehicle carried circuit l is not disturbed under the conditions described, and that therefore the vehicle carried element c receives sufficient energy from the energizing element a to operate the relay H when the contact 65 is closed. It will be also noted that even though the cooperation between the resetting inductors e and e' is but momentary, the relay H remains energized when the vehicle passes the control point due to the closing of the stick contact 36 of the circuit l when the relay H is energized.

Under "danger" track conditions due to the deenergization of both the roadside inductor circuits m and n, both relays F and H are deenergized and the valve V is operated to bring the vehicle to a halt. For the purpose of permitting the train to proceed after thus being brought to a halt, there may be provided a manually reset circuit which includes the conductor 73, the switch 74 and the conductor 75 arranged in parallel with the reset contact 65, the closing of the switch 74 effecting the closing of the vehicle carried circuit l, this to permit the train to proceed under restriction to the next control station.

Although in the embodiment illustrated in the drawings and hereinbefore described, the vehicle carried and roadside inductor means are designed to cooperate for producing "clear", "caution" and "danger" indications on the train, it will be understood that the principles of my invention may be employed for producing any number of train indications. For example, the inductive system may consist merely in the combination of inductors for producing "proceed" and "stop" effects on the train mechanism. With such a construction the inductors a, b and d cooperating with the inductors a', b' and d' would be employed, the roadside inductors functioning for influencing the vehicle inductors to produce a controlling condition and for being influenced by the vehicle inductors for pro-

ducing a modification of the controlling condition, a single inductor circuit on the roadside being thus employed for producing the tripping effect and the resetting effect.

Referring now to Fig. 2 of the drawings, I show means for amplifying the current inductively received by the vehicle carried inductors d and e , the said means comprising generators designated generally as G' and G^2 , generator G' being inserted in the circuit p and generator G^2 in the circuit o . Each generator may be of the induction motor type, the generator G' having the rotor 77 and the field 78, and generator G^2 having the rotor 77' and the field 78'. In each generator the rotor is driven by a motor (not shown) which may for example be a turbine. With the train control system in operation, the rotors of these generators are continuously operated, and whenever the inductors d and e become energized by their corresponding track inductors, energy is induced in the windings or stators of the generators, with the result that in effect the amplification takes place for the moment, considerably increasing the amount of energy through the armatures f^3 and h^4 of the indication receivers F' and H' .

Referring now to Fig. 3 of the drawings, I show a modification of the amplifying means employed in the inductor circuits p and o , each inductor circuit being provided with a generator which may be of the direct current type, the circuit p being provided with the generator G^3 and the circuit o being provided with the generator G^4 . It will be noted that the circuit including the inductor e includes the conductor 79, condenser 80, winding 81 of the field pole 82, conductor 83, winding 84 of the field pole 85, and conductor 86. The armature h^4 of the indication receiver H' includes in its circuit conductor 87, condenser 88, conductor 89, winding 90 on the field pole 82, conductor 91, armature 92, conductor 93, winding 94 on the field pole 85, and conductor 95. It will be noted from this construction that the armature of the indication receiver cooperates with its inductor, but that the circuits connecting the two are separated. The generator G^4 comprises similar parts designated by primed reference characters. The condensers in the inductor parts of the circuits as well as in the armature parts of the circuits are provided for correction of power factor of the circuits, these condensers being preferably adjusted so as to place the circuits in the proper state of impedance. When the inductors d and e or either of them come into correspondence with their respective cooperating track inductors, as for example when the inductor e comes into correspondence with the track inductor e' , energy is induced in the inductor e , this in turn energizing the field of the generator G^3 momentarily, and

since the generator G^3 is operating as a generator, flux is set up in the field of the generator and a current is produced in the circuit p of the armature 92, with the result that the energy which was originally induced in the inductor e is magnified in its effect on the circuit p .

The operation of my train control system as a whole is substantially as follows: When the train is running without restriction, the vehicle carried relay F is in an energized state and the vehicle carried relay H is in a deenergized state with the valve magnet 10 energized to permit the train to proceed without limitation. When the train running without restriction reaches a control station indicating "clear", the vehicle carried inductor means A is uninfluenced by the roadside inductor means B and the relay F remains in an energized state. When such a train running without restriction reaches a control station indicating "caution", the train carried inductor means A cooperates with the roadside inductor means B to produce a deenergizing of the vehicle carried relay F and an energizing of the vehicle carried relay H , the valve magnet 10 being thereby placed under the control of the speed controller 21 to permit the train to proceed under a speed restriction, the speed control circuit comprising the generator G , conductors 19, 18 and 17, electromagnet 10, conductors 16 and 24, a contact 23, conductor 22, speed controller 21, and conductors 20, 12 and 11. When, however, a train running without restriction reaches a station indicating "danger", the vehicle carried inductor means A cooperates with the roadside inductor means B to deenergize the relay F , and since the relay H is in a deenergized state, the train control circuit h will be opened to deenergize the electromagnet 10 for bringing the vehicle to a halt, after which the switch 74 may be operated to permit the train to proceed to the next control station under a speed restriction. When a train is running under "caution" conditions, the vehicle carried relay F is in a deenergized state and the vehicle carried relay H is in an energized state. When the train which is running under such a "caution" restriction reaches a control station indicating "caution", the roadside inductor means B has no influence on the vehicle carried inductor means A , and the relay H remains energized to maintain the speed restrictive control of the train. When, however, a train running under a speed restriction reaches a station indicating "danger", the vehicle carried inductor means A cooperates with the roadside inductor means B to trip or deenergize the relay H , and since the relay F is in a deenergized state, the control circuit h will be opened to deenergize the magnet 10 to bring the vehicle to a halt, after which the switch 74 must be operated to per-

mit the train to proceed under restriction to the next control station.

While I have shown my invention in the preferred form, it will be obvious that many changes and modifications may be made in the structure disclosed without departing from the spirit of the invention, defined in the following claims.

I claim:

10. 1. In combination, vehicle carried mechanism, a vehicle carried inductor means including an energizing inductor associated with and adapted to be influenced for tripping the said vehicle carried mechanism, a second vehicle carried inductor means including an energy receiving inductor associated with and adapted to be influenced for resetting the vehicle carried mechanism, and a roadside inductor circuit embracing an inductor means 15 cooperating with said vehicle carried inductor means, said roadside inductor circuit being operable in response to a given roadside condition for influencing the first mentioned vehicle carried inductor means to produce the 20 tripping action and operable in response to another roadside condition for influencing the second vehicle carried inductor means to produce the resetting action.
2. In combination, vehicle carried mechanism, a vehicle carried inductor means including an energizing inductor associated with and adapted to be influenced for tripping the said vehicle carried mechanism, a second vehicle carried inductor means including an 25 energy receiving inductor associated with and adapted to be influenced for resetting the vehicle carried mechanism, and a roadside inductor circuit embracing a plurality of inductors spaced in correspondence with the vehicle carried inductors, said circuit being operable in response to a given roadside condition for influencing the first mentioned vehicle carried inductor means to produce the tripping action and operable in response to another roadside condition for influencing the second vehicle carried inductor means to produce the resetting action.
3. In combination, vehicle carried mechanism, a vehicle carried inductor means associated with and adapted to be influenced for tripping the said vehicle carried mechanism, a second vehicle carried inductor means associated with and adapted to be influenced for resetting the vehicle carried mechanism, and roadside means including an inductor and a circuit embracing the inductor, said circuit being operable in response to a given roadside condition for influencing the first mentioned vehicle carried inductor means to produce the tripping action and operable in response to another roadside condition for influencing the second vehicle carried inductor means to produce the resetting action.
4. In combination, vehicle carried mechanism, a vehicle carried inductor means associated with and adapted to be influenced for tripping the said vehicle carried mechanism, a second vehicle carried inductor means associated with and adapted to be influenced for resetting the vehicle carried mechanism, and a roadside means including a plurality of inductors and a circuit embracing the plurality of inductors, said circuit being operable when open for influencing the first mentioned vehicle carried inductor means to produce the tripping action and operable when closed for influencing the second vehicle carried inductor means to produce the resetting action.
5. In combination, vehicle carried mechanism, a vehicle carried energizing inductor associated with and adapted to be influenced for tripping the said vehicle carried mechanism, a second vehicle carried inductor associated with and adapted to be influenced for resetting the vehicle carried mechanism, and a roadside inductor means operable in response to a given roadside condition for influencing the energizing vehicle carried inductor to produce the tripping action and operable in response to another roadside condition for being energized by said energizing inductor for influencing the second vehicle carried inductor to produce the resetting action.
6. In combination, vehicle carried mechanism, a vehicle carried energizing inductor associated with and adapted to be influenced for tripping the said vehicle carried mechanism, a vehicle carried source of energy for said inductor, a second vehicle carried inductor associated with and adapted to be influenced for resetting the vehicle carried mechanism, and a roadside inductor means operable in response to a given roadside condition for influencing the energizing vehicle carried inductor to produce the tripping action and operable in response to another roadside condition for being energized by said energizing inductor for influencing the second vehicle carried inductor means to produce the resetting action.
7. In combination, vehicle carried mechanism including a normally closed operating circuit, a vehicle carried inductor means associated with and adapted to be influenced for opening the said circuit, a second vehicle carried inductor means associated with and adapted to be influenced for closing said circuit, and a roadside inductor circuit embracing an inductor means cooperating with said vehicle carried inductor means, said roadside inductor circuit being operable in response to a given roadside condition for influencing the first mentioned vehicle carried inductor means and operable in response to another roadside condition for influencing the second vehicle carried inductor means.
8. In combination, vehicle carried mechanism including a normally closed circuit, a

vehicle carried inductor means associated with and adapted to be influenced for opening the said circuit, a second vehicle carried inductor means associated with and adapted to be influenced for closing the said circuit, and a roadside means comprising a plurality of inductors and a circuit embracing the plurality of inductors, operable when open for influencing the first mentioned vehicle carried inductor means and operable when closed for influencing the second vehicle carried inductor means.

9. In combination, vehicle carried mechanism, a vehicle carried inductor means associated with and adapted to be influenced for producing a predetermined operation in the said vehicle carried mechanism, a second vehicle carried inductor means associated with and adapted to be influenced for modifying said operation of the vehicle carried mechanism, and a roadside inductor circuit embracing an inductor means cooperating with said vehicle carried inductor means, said roadside inductor circuit being operable in response to a given roadside condition for influencing the said first mentioned vehicle carried inductor means and operable in response to another roadside condition for influencing the second vehicle carried inductor means.

10. In combination, vehicle carried mechanism, a vehicle carried energizing inductor associated with and adapted to be influenced for producing a predetermined operation in the said vehicle carried mechanism, a second vehicle carried inductor associated with and adapted to be influenced for modifying said operation of the vehicle carried mechanism, and a roadside inductor means operable in response to a given roadside condition for influencing the energizing vehicle carried inductor and operable in response to another roadside condition for being energized by said energizing inductor for influencing the second vehicle carried inductor.

11. In combination, vehicle carried mechanism, a vehicle carried inductor means associated with and adapted to be influenced for producing a predetermined operation in the said vehicle carried mechanism, a second vehicle carried inductor means associated with and adapted to be influenced for modifying said operation of the vehicle carried mechanism, and a roadside inductor circuit embracing an inductor means cooperating with said vehicle carried inductor means, said roadside inductor circuit being operable in response to a "danger" roadside condition for influencing the said first mentioned vehicle carried inductor means and operable in response to a "safe" roadside condition for influencing the second vehicle carried inductor means.

12. In combination, vehicle carried mechanism, a vehicle carried inductor means associated with and adapted to be influenced for producing a predetermined operation in the

said vehicle carried mechanism, a second vehicle carried inductor means associated with and adapted to be influenced for modifying said operation of the vehicle carried mechanism, and a roadside inductor circuit embracing an inductor means cooperating with said vehicle carried inductor means, said roadside inductor circuit being operable in response to a "caution" roadside condition for influencing the said first mentioned vehicle carried inductor means and operable in response to a "safe" roadside condition for influencing the second vehicle carried inductor means.

13. In combination, vehicle carried mechanism, a vehicle carried inductor means including an energizing inductor associated with and adapted to be influenced for tripping the said vehicle carried mechanism, a second vehicle carried inductor means including an energy receiving inductor associated with and adapted to be influenced for resetting the vehicle carried mechanism and a roadside inductorium means operable in response to a given roadside condition for influencing the first mentioned inductor means to produce the tripping action and operable in response to another roadside condition for influencing the second vehicle carried inductor means to produce the resetting action when the vehicle carried mechanism has been tripped and being inoperative under such last mentioned condition for producing any change in said vehicle carried mechanism when the said vehicle carried mechanism has not been tripped.

14. In combination, vehicle carried mechanism, a vehicle carried energizing inductor associated with and adapted to be influenced for tripping the said vehicle carried mechanism, a second vehicle carried inductor associated with and adapted to be influenced for resetting the vehicle carried mechanism and a roadside inductorium means operable in response to a given roadside condition for influencing the first mentioned inductor to produce the tripping action and operable in response to another roadside condition for receiving energy from the energizing inductor for influencing the second vehicle carried inductor to produce the resetting action when the vehicle carried mechanism has been tripped and being inoperative under such last mentioned condition for producing any change in said vehicle carried mechanism when the said vehicle carried mechanism has not been tripped.

15. In combination, vehicle carried mechanism, a vehicle carried inductor means associated with and adapted to be influenced for tripping the said vehicle carried mechanism, a second vehicle carried inductor means associated with and adapted to be influenced for resetting the vehicle carried mechanism; and a roadside means including

- spaced inductors, and a circuit embracing the spaced inductors, operable in response to a given roadside condition for influencing the first mentioned inductor means to produce the tripping action and operable in response to another roadside condition for influencing the second vehicle carried inductor means to produce the resetting action when the vehicle carried mechanism has been tripped and being inoperative under such last mentioned condition for producing any change in said vehicle carried mechanism when the said vehicle carried mechanism has not been tripped.
16. In combination, vehicle carried mechanism, a vehicle carried inductor means associated with and adapted to be influenced for tripping the said vehicle carried mechanism, a second vehicle carried inductor means associated with and adapted to be influenced for resetting the vehicle carried mechanism; and a roadside means including a plurality of inductors, and a circuit embracing the plurality of inductors operable when open for influencing the first mentioned inductor means to produce the tripping action and operable when closed for influencing the second vehicle carried inductor means to produce the resetting action when the vehicle carried mechanism has been tripped and being inoperative when closed for producing any change in said vehicle carried mechanism when the said vehicle carried mechanism has not been tripped.
17. In combination, vehicle carried mechanism comprising a control relay, a circuit therefor and an inductor in said circuit adapted to be influenced for producing a predetermined operation of said relay, a resetting circuit for said relay, an indication receiver for operating the resetting circuit and a second inductor adapted to be influenced for operating the indication receiver; and roadside mechanism comprising a roadside inductor, and circuit governing the same operable in response to a given roadside condition for influencing said first mentioned vehicle carried inductor and operable in response to another roadside condition for influencing the second vehicle carried inductor.
18. In combination, vehicle carried mechanism comprising a control relay, a transformer including primary and secondary coils associated therewith, the said primary coil being adapted to be influenced for producing a predetermined operation of said relay, a resetting circuit for said relay, an indication receiver for operating the resetting circuit and an inductor adapted to be influenced for operating the indication receiver; and roadside mechanism comprising a roadside inductor, and a circuit for said inductor operable in response to a given roadside condition for directly influencing said primary coil and operable in response to another roadside condition for influencing the said vehicle carried inductor.
19. In combination, vehicle carried mechanism comprising a control relay, a transformer including primary and secondary coils associated therewith, the said primary coil being adapted to be influenced for producing a predetermined operation of said relay, a resetting circuit for said relay, an indication receiver for operating the resetting circuit and an inductor adapted to be influenced for operating the indication receiver; and roadside mechanism comprising a roadside inductor means operable in response to a given roadside condition for influencing said primary coil and operable in response to another roadside condition for being energized by said primary coil for influencing the said vehicle carried inductor.
20. In combination, vehicle carried mechanism comprising a control relay, a circuit therefor and an inductor in said circuit adapted to be influenced for producing a predetermined operation of said relay, a resetting circuit for said relay, an indication receiver for operating the resetting circuit and a second inductor adapted to be influenced for operating the indication receiver; and roadside mechanism comprising inductor means, and a roadside circuit embracing the inductor means operable when open for influencing said first mentioned vehicle carried inductor and operable when closed for influencing the second vehicle carried inductor.
21. In combination, vehicle carried mechanism comprising a control relay, a normally closed circuit therefor and an inductor in said circuit adapted to be influenced for opening the circuit to trip said relay, a resetting circuit for said relay, an indication receiver for operating the resetting circuit and a second inductor adapted to be influenced for operating the indication receiver; and roadside mechanism comprising a combined tripping and resetting inductor means combined in one circuit and operable in response to a given roadside condition for influencing said first mentioned vehicle carried inductor and operable in response to another roadside condition for influencing the second vehicle carried inductor.
22. In combination, vehicle carried mechanism comprising a control relay, a normally closed stick circuit therefor and an inductor in said circuit adapted to be influenced for opening the circuit to trip said relay, a resetting circuit for said relay, an indication receiver for operating the resetting circuit and a second indicator adapted to be influenced for operating the indication receiver; and roadside mechanism comprising a roadside inductor means and a normally closed circuit therefor operable when open for in-

fluencing said first mentioned vehicle carried inductor and operable when closed for influencing the second vehicle carried inductor.

23. In combination, vehicle carried mechanism selectively operable for producing different train control effects, a vehicle carried inductor means associated with and adapted to be influenced for tripping the said vehicle carried mechanism, a second vehicle carried inductor means associated with and adapted to be selectively influenced for resetting the vehicle carried mechanism, and a mechanism comprising a combined tripping and resetting inductor means combined in one circuit 10 and operable in response to a given roadside condition for influencing the first mentioned vehicle carried inductor means to produce the tripping action and selectively operable in response to either of two other roadside 15 conditions for selectively influencing the second vehicle carried inductor means to produce the selective resetting action.

24. In combination, vehicle carried mechanism selectively operable for producing different train control effects, a vehicle carried inductor means associated with and adapted to be influenced for tripping the said vehicle carried mechanism, a second vehicle carried inductor means including a plurality of impulse receiving inductors associated with and adapted to be selectively influenced for resetting the vehicle carried mechanism, and a roadside inductor means including a plurality of impulse transmitting 30 inductors operable in response to a given roadside condition for influencing the first mentioned vehicle carried inductor means to produce the tripping action and selectively operable in response to either of two other 35 roadside conditions for selectively influencing the second vehicle carried inductor means to produce the selective resetting action.

25. In combination, vehicle carried mechanism selectively operable for producing different train control effects, a vehicle carried inductor means associated with and adapted to be influenced for tripping the said vehicle carried mechanism, a second vehicle carried inductor means associated with and adapted 50 to be selectively influenced for resetting the vehicle carried mechanism, and roadside means including an inductor circuit operable in response to a given roadside condition for influencing the first mentioned vehicle carried inductor means to produce the tripping action and selectively operable in response to either of two other roadside conditions for selectively influencing the second vehicle carried inductor means to produce the selective 55 resetting action.

26. In combination, vehicle carried mechanism selectively operable for producing different train control effects, a vehicle carried inductor means associated with and adapted to be influenced for tripping the said 60

vehicle carried mechanism, a second vehicle carried inductor means associated with and adapted to be selectively influenced for resetting the vehicle carried mechanism, and a roadside means including a circuit having an impulse receiving inductor and a plurality of impulse transmitting inductors operable in response to a given roadside condition for influencing the first mentioned vehicle carried inductor means to produce the tripping action and selectively operable in response to either of two other roadside conditions for selectively influencing the second vehicle carried inductor means to produce the selective resetting action. 70

27. In combination, vehicle carried mechanism selectively operable for producing different train control effects, a vehicle carried energizing inductor associated with and adapted to be influenced for tripping the said vehicle carried mechanism, a second vehicle carried inductor means associated with and adapted to be selectively influenced for resetting the vehicle carried mechanism, and a roadside inductor means operable in response to a given roadside condition for influencing the energizing vehicle carried inductor to produce the tripping action and selectively operable in response to either of two other roadside conditions for being energized by said energizing inductor for selectively influencing the second vehicle carried inductor means to produce the selective resetting action. 80

28. In combination, vehicle carried mechanism selectively operable for producing different train control effects, a vehicle carried inductor means associated with and adapted to be influenced for tripping the said vehicle carried mechanism, a second vehicle carried inductor means associated with and adapted to be selectively influenced for resetting the vehicle carried mechanism, and a roadside inductor means including a receiving inductor, two transmitting inductors and changeable circuit connections therebetween operable in response to a given roadside condition for influencing the first mentioned vehicle carried inductor means to produce the tripping action and selectively operable in response to either of two other roadside conditions for selectively influencing the second vehicle carried inductor means to produce the selective resetting action. 100

29. In combination, vehicle carried mechanism including a plurality of circuits selectively closable for producing different train control effects, a vehicle carried inductor means associated with and adapted to be influenced for opening either of the closable circuits, a second vehicle carried inductor means associated with and adapted to be influenced for selectively resetting the circuits, and a roadside inductor means operable in response to a given roadside condition for in- 115

120

130

fluencing the first mentioned vehicle carried inductor means and selectively operable in response to either of two other roadside conditions for selectively influencing the second vehicle carried inductor means.

30. In combination, vehicle carried mechanism including a plurality of circuits selectively closable for producing different train control effects, a vehicle carried inductor means associated with and adapted to be influenced for opening either of the closable circuits, a second vehicle carried inductor means associated with and adapted to be influenced for selectively resetting the said circuits, and a roadside means including a circuit having a plurality of inductors and changeable circuit connections operable when open for influencing the first mentioned vehicle carried inductor means to produce the tripping action and selectively operable when closed in different manners for selectively influencing the second vehicle carried inductor means to produce the selective resetting action.

31. In an inductive train control system, vehicle carried mechanism selectively operable for producing different train control effects comprising a vehicle carried control relay mechanism, circuit means therefor, an inductor in said circuit means adapted to be influenced for producing a predetermined operation of said relay mechanism, resetting circuits for said relay mechanism, an indication receiver means selectively operable for operating said reset circuits and a plurality of vehicle carried inductors for said indication receiver means; and roadside mechanism comprising a roadside inductor means operable in response to a given roadside condition for influencing said first mentioned vehicle carried inductor and operable in response to either of two other roadside conditions for selectively influencing the said plurality of vehicle carried inductors.

32. In an inductive train control system, vehicle carried mechanism selectively operable for producing different train control effects comprising a vehicle carried control relay mechanism, a transformer including primary and secondary coils associated therewith, the said primary coil being adapted to be influenced for producing a predetermined operation of said relay mechanism, resetting circuits for said relay mechanism, an indication receiver means selectively operable for operating said reset circuits and a plurality of vehicle carried inductors for said indication receiver means; and roadside mechanism comprising a roadside inductor means operable in response to a given roadside condition for influencing said primary coil and operable in response to either of two other roadside conditions for selectively influencing the said plurality of vehicle carried inductors.

33. In an inductive train control system,

vehicle carried mechanism selectively operable for producing different train control effects comprising a vehicle carried control relay mechanism, a transformer including primary and secondary coils associated therewith, the said primary coil being adapted to be influenced for producing a predetermined operation of said relay mechanism, resetting circuits for said relay mechanism, an indication receiver means selectively operable for operating said reset circuits and a plurality of vehicle carried inductors for said indication receiver means; and roadside mechanism comprising a roadside inductor means operable in response to a given roadside condition for influencing said primary coil and operable in response to either of two other roadside conditions for being energized by said primary coil for selectively influencing the said plurality of vehicle carried inductors.

34. In an inductive train control system, vehicle carried mechanism selectively operable for producing different train control effects comprising a plurality of vehicle carried control relays, a circuit for each relay, and inductor in each circuit, an energizing inductor common to both circuits adapted to be influenced for producing a predetermined operation of either relay, a plurality of resetting circuits one for each relay, an indication receiver for each reset circuit and a vehicle carried inductor for each indication receiver; and roadside mechanism comprising a roadside inductor means operable in response to a given roadside condition for influencing said energizing inductor and operable in response to either of two other roadside conditions for selectively influencing the other vehicle carried inductors.

35. In an inductive train control system, vehicle carried mechanism selectively operable for producing different train control effects comprising a plurality of vehicle carried control relays, a circuit for each relay, an inductor in each circuit, an energizing inductor common to both circuits adapted to be influenced for producing a predetermined operation of either relay, a plurality of resetting circuits one for each relay, an indication receiver for each reset circuit and a vehicle carried inductor for each indication receiver; and roadside mechanism comprising an inductor for each indication receiver; and roadside mechanism comprising an inductor arranged to receive energy from the vehicle energizing inductor, a plurality of inductors arranged to transmit energy to said vehicle carried inductors, and changeable circuit connections between said roadside inductors.

36. In an inductive train control system, vehicle carried mechanism selectively operable for producing different train control effects comprising a plurality of vehicle carried control relays, a circuit for each relay,

- an inductor in each circuit, an energizing inductor common to both circuits adapted to be influenced for producing a predetermined operation of either relay, a plurality of resetting circuits one for each relay, an indication receiver for each reset circuit and a vehicle carried inductor for each indication receiver; and roadside mechanism comprising an inductor arranged to correspond with said vehicle carried energizing inductor, a plurality of inductors arranged to correspond with the other vehicle inductors, circuit means connecting the roadside inductors and means for breaking and changing circuit connections between the roadside inductors. 5
37. In combination, vehicle carried mechanism, a vehicle carried inductor means associated with and adapted to be influenced for tripping and for resetting the said vehicle carried mechanism, said vehicle carried inductor means including an energizing inductor; and a roadside inductor means cooperating with said vehicle carried inductor means, said roadside inductor means including a roadside inductor element devoid of an energy source cooperable directly with said energizing inductor in response to a given roadside condition for producing the tripping action and cooperable directly with said energizing inductor in response to another roadside condition for producing the resetting action of said vehicle carried mechanism. 10
38. In combination, vehicle carried mechanism, a vehicle carried inductor means associated with and adapted to be influenced for tripping and for resetting the said vehicle carried mechanism, said vehicle carried inductor means including an energizing inductor and an energy receiving inductor coupled thereto; and a roadside inductor means cooperating with said vehicle carried inductor means, said roadside inductor means including a roadside inductor element cooperable with said energizing inductor in response to a given roadside condition for producing the tripping action and cooperable with said energizing inductor in response to another roadside condition for producing the resetting action of said vehicle carried mechanism. 15
39. In combination, vehicle carried mechanism, a vehicle carried inductor means associated with and adapted to be influenced for tripping and for resetting the said vehicle carried mechanism, said vehicle carried inductor means including an energizing inductor; and a roadside inductor means cooperating with said vehicle carried inductor means, said roadside inductor means including a circuit devoid of an energy source and a roadside inductor element in said circuit cooperable with said energizing inductor in response to a given roadside condition for producing the tripping action and cooperable with said energizing inductor in response to another roadside condition for producing the resetting action of said vehicle carried mechanism. 20
40. In combination, vehicle carried mechanism, a vehicle carried inductor means associated with and adapted to be influenced for tripping and for resetting the said vehicle carried mechanism, said vehicle carried inductor means including an energizing inductor, and an A. C. source of energy therefor; and a roadside inductor means cooperating with said vehicle carried inductor means, said roadside inductor means including a roadside inductor element cooperable with said energizing inductor in response to a given roadside condition for producing the tripping action and cooperable with said energizing inductor in response to another roadside condition for producing the resetting action of said vehicle carried mechanism. 25
41. In combination, vehicle carried mechanism, a vehicle carried inductor means associated with an adapted to be influenced for tripping and for resetting the said vehicle carried mechanism, said vehicle carried inductor means including an energizing inductor; and a roadside inductor means cooperating with said vehicle carried inductor means, said roadside inductor means including a circuit devoid of an energy source and a roadside inductor element in said circuit cooperable with said energizing inductor in response to a given roadside condition for producing the tripping action of said vehicle carried mechanism when said circuit is open and cooperable with said energizing inductor in response to another roadside condition for producing the resetting action of said vehicle carried mechanism when said circuit is closed. 30
42. In combination, vehicle carried mechanism, a vehicle carried inductor means associated with and adapted to be influenced for tripping and for resetting the said vehicle carried mechanism, said vehicle carried inductor means including an energizing inductor, an energy receiving inductor coupled thereto and an A. C. energy source therefor; and a roadside inductor means cooperating with said vehicle carried inductor means, said roadside inductor means including a roadside inductor element cooperable with said energizing inductor in response to a given roadside condition for producing the tripping action and cooperable with said energizing inductor in response to another roadside condition for producing the resetting action of said vehicle carried mechanism. 35
43. In a train control system, a normally energized vehicle carried element supplied with A. C., a roadside element inductively associated with the vehicle element, a train control phase relay controlled by the power factor of the vehicle element, and a holding means for the phase relay releasable by co-action of the vehicle and roadside elements. 40
44. In a train control system, a normally 45

energized vehicle carried element supplied with A. C., a roadside element inductively associated with the vehicle element, a train control phase relay controlled by the power factor of the vehicle element, and a holding means for the phase relay releasable by variation of the magnetic characteristics of the vehicle element.

45. In a train control system, a phase relay, 10 a holding means for the relay, vehicle carried coils normally energized and controlling respectively the relay and the holding means, and roadside means, inductively associated with the vehicle means, to vary the control 15 by the vehicle means.

46. An intermittent inductive train control system comprising in combination, vehicle carried mechanism including inductively coupled elements normally coupled together 20 for direct energy transference therebetween, a circuit for the vehicle carried mechanism controlled by said coupled elements, said circuit having a normal impedance such as to normally permit energization of the circuit, 25 and roadside mechanism including a roadside inductor cooperating inductively with the vehicle carried inductively coupled elements when said elements move over and in proximity to said roadside inductor in the movement 30 of the vehicle over the roadside for changing the impedance of said controlled circuit to effectively deenergize the circuit and to produce an operation in said vehicle carried mechanism.

35 47. An intermittent inductive train control system comprising in combination, vehicle carried mechanism including inductively coupled elements normally coupled together for direct energy transference therebetween, 40 a normally resonant circuit for the vehicle carried mechanism controlled by said coupled elements, and roadside mechanism including a roadside inductor cooperating inductively with the vehicle carried inductively coupled 45 element when said elements move over and in proximity to said roadside inductor in the movement of the vehicle over the roadside for making said controlled circuit non-resonant to produce an operation in said vehicle 50 carried mechanism.

48. An intermittent inductive train control system comprising in combination, vehicle carried mechanism including inductively coupled coils normally coupled together for direct energy transference therebetween, a circuit for the vehicle carried mechanism having a normally low impedance controlled by said coupled coils, and roadside mechanism including a roadside 55 inductor cooperating inductively with the vehicle carried inductively coupled coils when said coils move over and in proximity to said roadside inductor in the movement of the vehicle over the roadside for increasing 60 the impedance of said controlled circuit to 65

produce a tripping operation in said vehicle carried mechanism, and a roadside circuit for said roadside inductor operative when closed to prevent the said tripping operation thereof.

49. An intermittent inductive train control system comprising in combination, vehicle carried mechanism including a source of energy, a train controlling device, an energy transmitting coil connected to said source of energy, an energy receiving coil normally inductively coupled to said energy transmitting coil for receiving energy therefrom and connected in circuit to said controlling device, said circuit having means for predetermining the impedance of the circuit to permit energization of said circuit, and roadside mechanism including an inductor member cooperating inductively with the vehicle carried energy transmitting and receiving coils when said coils move over and in proximity to said inductor member for changing the impedance of said vehicle carried circuit to effectively deenergize the circuit so as to operate the vehicle carried mechanism.

50. An intermittent inductive train control system comprising in combination, vehicle carried mechanism including a source of energy, a train controlling device, an energy transmitting coil connected to said source of energy, an energy receiving coil normally inductively coupled to said energy transmitting coil for receiving energy therefrom and connected in circuit to said controlling device, said circuit having means for rendering the same normally resonant, and roadside mechanism including an inductor member cooperating inductively with the vehicle carried energy transmitting and receiving coils when said coils move over and in proximity to said inductor member for changing the resonance characteristics of said vehicle carried circuit to operate the vehicle carried mechanism.

51. An intermittent inductive train control system comprising in combination, vehicle carried mechanism including a source of energy, a train controlling device, an energy transmitting coil connected to said source of energy, an energy receiving coil normally inductively coupled to said energy transmitting coil for receiving energy therefrom and connected in circuit to said controlling device, said circuit having means for predetermining the impedance of the circuit to permit normal energization of the circuit, and roadside mechanism including an inductor member cooperating inductively with the vehicle carried energy transmitting and receiving coils when said coils move over and in proximity to said inductor member for increasing the impedance of said vehicle carried circuit to trip the vehicle carried mechanism, and a circuit for said roadside induc- 130

tor member for inhibiting the tripping operation thereof.

52. An intermittent inductive train control system comprising in combination, vehicle carried mechanism including a source of energy, a train controlling device, an energy transmitting coil connected to said source of energy, an energy receiving coil normally inductively coupled to said energy transmitting coil for receiving energy therefrom and connected in circuit to said controlling device, said circuit having means for predetermining the impedance of the circuit, and roadside mechanism including an inductor member cooperating inductively with the vehicle carried energy transmitting and receiving coils when said coils move over and in proximity to said inductor member for changing the impedance of

10 said vehicle carried circuit to trip the vehicle carried mechanism; and means for resetting said mechanism energized from said vehicle carried energy transmitting coil.

53. An intermittent inductive train control system comprising in combination, vehicle carried mechanism including a source of energy, a train controlling device, an energy transmitting coil connected to said source of energy, an energy receiving coil normally inductively coupled to said energy transmitting coil for receiving energy therefrom and connected in circuit to said controlling device, said circuit having means for rendering the same normally resonant, and roadside mechanism including an inductor member cooperating inductively with the vehicle carried energy transmitting and receiving coils when said coils move over and in proximity to said inductor member for changing the resonance characteristics of said vehicle carried circuit to trip the vehicle carried mechanism, and a circuit for said roadside inductor member embodying means for correcting the impedance factor thereof and operable

25 40 45

when closed for inhibiting the tripping operation of the roadside inductor member.

54. An intermittent inductive train control system comprising in combination, vehicle carried mechanism including inductively coupled coils normally coupled together for direct energy transference therebetween, a circuit for the vehicle carried mechanism controlled by said coupled coils, said circuit having means for predetermining the impedance thereof, and roadside mechanism including a pair of roadside inductor elements arranged to correspond with the vehicle carried coils and operable when the said coils move over said inductor elements for changing the impedance of said controlled circuit, and a roadside circuit including coils for said roadside inductor elements, said roadside circuit when closed inhibiting the impedance-changing operation of said inductor elements.

55. An intermittent inductive train control system comprising in combination, vehicle carried mechanism including inductively coupled coils normally coupled together for direct energy transference therebetween, a circuit for the vehicle carried mechanism controlled by said coupled coils, said circuit having means for making the same normally resonant, and roadside mechanism including a pair of roadside inductor elements arranged to correspond with the vehicle carried coils and operable when the said coils move over said inductor elements for changing the resonance characteristics of said controlled circuit, and a roadside circuit including coils for said roadside inductor elements, said roadside circuit when closed inhibiting the resonance changing operation of said inductor elements.

56. An intermittent inductive train control system comprising in combination, vehicle carried mechanism including inductively coupled coils normally coupled together for direct energy transference therebetween, a circuit for the vehicle carried mechanism controlled by said coupled coils, said circuit having capacity and inductance components, and roadside mechanism including a pair of roadside inductor elements arranged to correspond with the vehicle carried coils, and a roadside circuit including coils for said roadside inductor elements, said roadside circuit also having capacity and inductance components.

57. An intermittent inductive train control system comprising in combination, vehicle carried mechanism including inductively coupled coils normally coupled together for direct energy transference therebetween, a circuit for the vehicle carried mechanism controlled by said coupled coils, said circuit having means for predetermining the impedance thereof, and roadside mechanism including a pair of roadside inductor elements arranged to correspond with the vehicle carried coils and operable when the said coils move over said inductor elements for changing the impedance of said controlled circuit to trip the same, a roadside circuit including coils for said roadside inductor elements, said roadside circuit when closed inhibiting the impedance-changing and tripping operation of said inductor elements, and vehicle carried and roadside inductor means energizable from said vehicle carried coupled coils for resetting said mechanism.

Signed at Niagara Falls, in the county of Niagara and State of New York, this 18th day of April, A. D. 1923.

FRED M. ROSENZWEIG.
